ROTARY FURNACE

George F. Blasier, North Tonawanda, N. Y., assignor to Buffalo Bolt Company, North Tonawanda, N. Y., a corporation of New York

Application December 17, 1937, Serial No. 180,300

28 Claims. (Cl. 263—33)

This invention relates more particularly to furnaces of the rotary tubular type, wherein rotation of the furnace is utilized for introducing, advancing and discharging articles or materials while progressively heating them by flame discharging into the furnace through the exit end thereof.

The present illustrative form was primarily designed and is herein shown as embodied in a furnace for annealing and heat treatment of metal articles such as steel nuts, bolts, or the like, but it will be obvious that various novel features of construction and operation of my furnace will be found useful in other rotary tube furnaces, and for heat treatment of other articles or materials, for other purposes.

As shown herein, the outer tubular shell, and the rotating, intake, exit, and flame-projecting arrangements, may be in a general way, similar to those shown in the U. S. patent to Rockwell, No. 1,333,343; but the present invention relates more particularly to a novel inner shell construction in place of the inner lining; novel means for supporting said inner shell in said outer tubular shell independently of the intermediate insulation; a novel construction for the means whereby rotation of said shell propels the articles or materials from the intake to the exit end of the furnace; and also novel combinations of the various novel features with each other, and with said outer shell, and with its rotating, intake, exit, and flame-projecting arrangements.

In furnaces of the above type, the cylinder may be, say, 15 feet long, by three feet or more internal diameter, and the interior is provided with a helical flange or rib. When the cylinder is rotated, the articles are carried by the cylindrical and helical inner surfaces, up to where gravity causes them to successively and progressively fall downward so that the helical rib surfaces operate to propel the articles toward the exit end of the furnace.

For annealing and heat treatment of metal articles, the inner lining and the helical flange is subjected to rather high temperatures, and to correspondingly high variations of temperature. For instance, in a given case, the temperature adjacent the exit end of the cylinder may be something like 1500° F., while the temperature at the entrance end may be only 300° or 400° F. It results that both radial and longitudinal expansion and shrinkage of the inner lining varies greatly between the exit and the entrance; and in the aggregate, the total amount of longitudinal expansion and shrinkage is very substantial.

For these reasons, it has been common to make the inner lining and its ribs of cast iron. But cast iron is brittle and the castings are heavy, so the prior practice has been to build up the inner lining from cylindrical castings each having a section of the helical rib integral therewith. These cylindrical sections may be 15 inches to 18 inches wide, lengthwise of the furnace, so that it may take 8 or 10 of them to complete an inner lining. They are supported by an intermediate lining consisting of arch brick resting on the exterior cylinder and presenting inner circular surfaces which support the cylindrical castings. In practice, the arch brick interlining with the successive cast iron sections thereon, is built up progressively from one end of the furnace to the other.

There are many objections to such constructions. One obvious objection is that the weight of the separate inner castings, the continuous rotation of the furnace, and the repeated expansion and contraction of the cast iron due to lighting up and turning off the heat, cause the castings to pound themselves loose in the brick, and in time this necessitates re-bricking and re-lining the entire furnace; and, in many cases the inner cast iron sections are so badly distorted by the heat that they cannot be re-used.

In this connection, it is to be noted that both the arch brick and the cast iron cylinder sections afford substantially no resistance to longitudinal tension, and they can contribute to transverse stiffness of the rotating furnace as compression members only; and their effectiveness even for this purpose depends on careful fit against one another and against the exterior shell. But the cast iron inner lining and the arch brick have substantially different coefficients of expansion; also the amount of the expansion and contraction of the inner cast iron, is different from that of the outer iron shell, because of the great difference in temperature between the interior which is directly heated and the exterior which is relatively cool because it is protected by intervening insulation, and is cooled by the outer air.

The present invention obviates these objectionable features by introducing an entirely new principle of construction.

In place of the many relatively short cast iron sections, I substitute a single integral tubular shell running the entire length of the furnace. Preferably, this is made from rolled, heat-resisting steel sheet or plate material, of thickness and construction such that said inner tube shell may

have nearly or quite as great strength as the outer shell.

This inner tube shell is anchored to the exterior shell at one place only, preferably at the exit opening where the finished articles fall out of the furnace. This would not be possible with the old type construction described above, because any radial expansion of the sectional cast rings would cause them to lodge or bind tightly against 10 the insulating brick, thereby preventing free expansion longitudinally of the furnace.

My inner tube shell is mounted in the outer shell by bearing surfaces which permit it to be inserted and removed endwise, as a unit, and 15 which permit it, when heated, to expand longitudinally by sliding in both directions from the above described anchorage point.

The supports permitting such endwise sliding, are rings fastened to the outer shell, and they 20 have bearing members extending inward a distance equal to the thickness desired for the heat insulation; and the insulation itself is suitable refractory aggregate which can be inserted in or removed from the interspace without disturbing 25 either the outer shell or the inner shell.

Another feature is making the inner propelling members in the form of short lengths of helically disposed bar material, each length being secured to the inside of the inner shell, by riveting, or 30 by welding, or preferably by both; and preferably at certain spaced-apart points, so that the expansion and contraction of these members may be somewhat different from that of the inner shell, without thereby distorting either themselves, or said shell.

The above and other features of my invention may be more fully understood from the following description in connection with the accompanying drawings, in which

40 Fig. 1 is a longitudinal sectional view in a vertical plane including the axis of the furnace and corresponding to the line 1—1, Fig. 3;

Fig. 1a is a similar section of a characteristic short length of the cylinder, but on a large scale 45 so as to facilitate illustrations of some details;

Fig. 2 is a diagram showing the inner cylindrical surface of the furnace, the entire circumference of the cylinder being unrolled to the vertical plane of an up-turning straight line element, so 50 as to give a diagrammatic indication of the disposition and operation of the successively upturning helical flights, with respect to gravity;

Fig. 3 is an end view of the furnace, from the left, Fig. 1;

55 Fig. 4 is a transverse section on the line 4—4, Fig. 1, the granular insulating material being omitted;

Fig. 5 is a detailed perspective showing the laterally corrugated rings whereby the inner shell 60 of the furnace is supported slidably but keyed against the rotation;

Fig. 6 is a detailed view of the inner shell and one of the key strips shown in Fig. 4, but on a much larger scale;

65 Fig. 7 is a detailed view showing a portion of the inner cylinder and key strip, in perspective as well as in section.

Referring first to conventional features of one form of furnace to which my new principles of construction have been applied:

(a) The outer shell 1 is conventionally indicated as provided with riding rings 2, 2, and rolls 2a, 2a, whereby it is supported for rotation in the desired direction and at desired rates, by 70 any suitable mechanism, not shown, but which

preferably includes a variable speed electric motor.

(b) The articles are charged into the furnace through opening 3, and, as the furnace rotates, they slide to the larger diameter end of chamber 5 3a and are then picked up by the edge 3b of a slanting, more or less spiral scoop 3c, which extends to the peripheral wall of said chamber 3a. As the furnace rotates farther, gravity causes the articles to slide inward on the scoop, and 10 ultimately to fall into the furnace through the opening 3d.

(c) A stationary hood 4 at the exit end of the furnace, surrounds the annular path of travel of the open outlet through which the heated articles 15 fall out of the furnace. This hood is designed to limit escape of flame and hot gases from said outlet, particularly during the upper half of its rotation, when it is upwardly directed, and would otherwise tend to act as a chimney discharging 20 directly into the open air. The upper annulus 4 connects with a stationary chute 4a, into which the hot nuts or other articles fall when the outlet is downwardly directed as in Fig. 1. This chute 4a serves as a connection between furnace 25 and quench tank which may contain water or oil or other fluid for chilling or otherwise modifying the quality of the heated articles; or, in case of annealing, it may contain only air, for air-cooling.

(d) The burner 5, whereby flame is projected axially into the furnace, may be of any known or desired construction, as also the cooperating insulation through which the flame is discharged, 30 although some features of the latter are new, particularly as concerns the novel way in which the insulation is supported by the furnace.

For my purposes, the outer shell 1, is preferably made of rolled plate of thickness and strength sufficient to carry the load of the entire 40 rotating structure, say, $\frac{1}{4}$ inch thick; and the cylinder may be built up from the plate material in any of the ordinary ways, as by riveting and welding, but for my purposes the inwardly presented ends of the rivets are preferably flush 45 with the interior surface of the shell.

The inner shell may be made from rolled steel sheets or plates, of considerable thickness and of heat-resisting qualities adequate for sustaining the structural strains and the maximum temperatures above indicated. For such reasons, 50 the inner shell is preferably thicker than the outer shell, say, $\frac{3}{8}$ inch instead of $\frac{1}{4}$ inch.

An important feature of this inner shell is making it externally smooth and uniform enough 55 so that it will be endwise slidable when it lengthens by heating or shortens by cooling; preferably also for easy endwise insertion into and removal from the outer shell. For these and other reasons, a novel construction in accordance with my present invention is highly desirable. In 60 my construction, the inner shell is made from a plurality of rolled metal plates extending the full length of the furnace. These long plates or strips are transversely curved on the arc of a circle of the diameter desired for the inner shell. As shown in Fig. 4 and also on a larger scale in Figs. 6 and 7, there are preferably only two such strips 6a, 6a, each transversely curved 65 to form a semi-cylinder. These semi-cylinders are assembled in a practically integral cylinder without any joints or projections except at the meeting edges of the semi-cylinders. A very effective way of making this joint, is to place the edges of the sheets in registering contact, 70 75

before inserting them in the outer shell. Then a long plate or strip $6b$, which may be, say, 3 inches wide, is secured over the contacting edges of the sections by rivets $6c$. Then the two corners where the edges of the strip contact the outer surface of the shell, are welded throughout the length of the shell, as indicated at $6d$. A long rectangular bar $6e$, is next placed edge-wise along the center of this strip, and welded 10 to it throughout its entire length as indicated at $6f$. These bars $6d$, $6e$ are utilized as a spline whereby the inner shell is endwise slidable, but is keyed against rotation.

As shown in Fig. 1, this inner shell is slidably supported in the outer shell, by end bearings, 15 and by suitably spaced intermediate bearings 7 , 7 ; which latter are preferably castings of metal capable of withstanding high temperature, preferably a nickel-chrome alloy such as Misco. As 20 shown in Fig. 5, each bearing 7 is an annulus of relatively thin metal reversely curved in transverse accordion-like flutings $1a$, of which the outer and inner edges, $1d$, $1e$, constitute cylindrically disposed bearing surfaces. The depth 25 of the flutings determines the effective width of the bearing surface lengthwise of the furnace. In a particular case, the flutings were 7 inches high radially; 3 inches lengthwise of the furnace; and the metal was $\frac{1}{8}$ inch thick.

30 Edgewise, the thin metal is substantially radial, so that the annulus affords rigid support for the inner shell; but the transverse flutings are springy, so that heat expansion or distortion of the annulus takes effect only as slight circumferential compression of said flutings, without any distorting or binding effect on the shells. To permit such functioning, the annulus is anchored to the outer shell only at intervals, with one, or preferably several, intervening flutings 35 unanchored; and, for similar reasons, the anchorages are preferably on adjacent convex bends on the same face of the casting, as indicated in Fig. 1 and Fig. 5, where angle fittings, $7b$, are shown as welded to the flutings and bolted to the outer shell.

40 As shown in Figs. 5 and 6, opposite flutings are cut away to form keyways $1c$ for the flat strips $6b$ and the key bars $6e$. As shown, there is substantial clearance space between the keys and keyways, as also between the inner shell 6 and the bearing rings 7 . Experience shows that with the construction described above, an all around clearance of about $\frac{1}{16}$ of an inch when the parts are cold, is sufficient. In practice, this 45 does not involve any undue looseness, it being only sufficient to allow a good endwise sliding fit when the furnace is hot.

There are also slidable bearings between inner and outer shells at each end of the furnace. 50 As shown in Fig. 1, the exit end of the inner shell 6 extends beyond the end of the outer shell 1 , and, as shown in Fig. 3, this end of the outer shell is closed in by an annulus which is made in two semi-circular sections, $1a$ and $1b$, secured 55 together by bolts, and, as indicated in Fig. 1, rigidly bolted to an angular annulus which is welded to the outer shell 1 . The end closure has a broad cylindrical extension $1c$ which, through an intermediate thin packing $1d$, affords a slidable bearing for this end of the inner shell.

60 At the other end, the inner surface of the inner shell 6 has slidable engagement with the outside surface of a projecting annulus $1e$, which is preferably cast on an end closure $1d$, which

is rigidly secured between ends of outer shell 1 , and supply chamber $3a$.

The six slidable bearings described above have incidental advantages in connection with the construction and assembly of the parts of the 5 furnace. When the end closures $1a$, $1b$, are removed, or before they are put in place, the inner shell 6 formed as above described, and provided with an outlet casting, $6x$, welded thereto, easily slides endwise through the ring bearings, until 10 its free end slides over the outer surface of said inwardly projecting annulus $1e$.

The anchorage of the inner shell to the outer shell is then effected by means of a somewhat larger outlet casting $1x$, which surrounds the 15 outlet casting $6x$ and is bolted to the outer shell 1 . The thin clearance space between these castings is then filled solid with refractory packing. Thus, the inner shell is securely anchored to the outer shell as concerns longitudinal movement; and as above described, the inner shell is free to expand longitudinally, in both directions from this anchorage, toward the firing end, and also toward the intake end. Thereafter the semi-circular closure sections $1a$, $1b$, are bolted to one 20 another and to the outer shell, thereby closing the interspace between shells and affording a 25 wide bearing surface on which this end of the inner shell may slide.

30 The projecting end of the inner shell 6 , carries the internally coned insulation $5a$ for spreading the flame, and this is preferably built in after said shell 6 has been put in place. Thereafter the smaller flame directing insulating members $5b$, $5c$, are arranged in the end closure $5h$ of 35 inner shell 6 , and said closure is then secured to the end of said inner shell 6 . The fuel projector 5 can be then placed in position.

40 After the inner shell 6 is in position, the interspaces between the ring bearings 7 , are filled 40 with refractory insulating material. As indicated at 8, 8, Figs. 1 and 2, this is preferably loose aggregate or lump material, preferably free from fine particles. This material may be broken fire brick, but I prefer a burnt slate product 45 known as "Haytite". A satisfactory range of the sizes for the lumps, includes such as will pass a one-inch screen and such as will not pass a half-inch screen. Such sizes are too large to pass through the clearance spaces between the inner 50 shell and the bearing surfaces; but in time tumbling of the loose aggregate during rotation, will wear off or break off some finer pieces, and these will tend to sift out through all bearing surfaces; and my construction is designed to obviate objectionable effects which would result.

55 Sifting out at the exit end of the furnace is made difficult, by having the broad close fitting bearing surface at $1c$, $1d$, but, as a further precaution, I provide a clamping ring $6g$; and, 60 after the furnace has been heated up and normal maximum expansion of the inner shell 6 has been effected, this ring is set tight against the end of bearing $1c$, and is rigidly clamped in place. When the furnace cools, causing endwise shrinkage toward the interior of the furnace, it also causes radial shrinkage, thereby relieving the tightness of the ring.

65 At the other end, where the inner shell has maximum longitudinal movement when contracted and expanded by heat, some difficulty is encountered, but this is taken care of by packing this interspace with steel turnings $8a$, which catch and hold any particles of aggregate that might otherwise escape in this direction. Pref- 70 75

erably the steel turnings are prevented from reaching the place where the free end of inner shell 6 slides on annulus 1e, by an annular partition 1f, which is rigidly secured to the outer shell 1, but is not secured to inner shell 6.

5 Sifting from one compartment to another, through the ring bearings 7, is not objectionable because the bearing surfaces afforded by the inner edges of the corrugations are too narrow to 10 permit any accumulation of the abraded insulating material, such as would prevent free endwise sliding of the shell.

15 Manholes of suitable size and location for packing the aggregate and steel turnings into the interspaces between the inner and outer shells are assumed; and are more or less diagrammatically indicated on Fig. 1 as having cover plates 1g, which are thick enough and are secured by bolts and nuts strong enough so that structural 20 strength of the outer shell 1, is not impaired by the manholes.

25 While a furnace such as above described might be mounted on an inclined axis so that progress of the articles or materials from entrance to 30 exit would be partly or even wholly, by rotary tumbling, the primary purpose of the whole design, is to successfully apply interior ribs or segments adapted to uniformly feed, tumble and heat a continuous stream of the articles or materials, when the axis is horizontal, or approximately so.

35 In the prior art, the ribs used for propelling the articles through the furnace, particularly those near the hot exit end of the furnace, are so high that their innermost edges are close to the axial flame whereby the furnace is heated, and said ribs necessarily get much hotter than the cylinder part of the casting. Consequently, 40 repeated heating and cooling brought about great distortion of the entire casting, so much so that the casting would break loose from the brick, and wreck the interior. Even before this happened, the helical rib segments would become misaligned, thereby affording lodging places 45 where some of the articles would be held and ruined by overheating. These primary conditions are what brought about my idea of making the inner lining continuous.

50 At first, I assumed that for my continuous inner lining I would have to have fairly high ribs, as in the prior art, and I tried a continuous helix made up in sections and secured to the inner lining by riveting and welding. These sections consisted of helical castings, L-shaped in cross-section, but with rib height only about 55 two inches.

55 However, I found in practice that even with this greatly reduced cross-section, unequal contraction and expansion by repeated heating and cooling, operated to greatly distort the continuous inner shell.

60 My next thought was to make the helix from rectangular sections of very much less height, approximately 1 inch high and 1½ inches wide. 65 This would afford only 1 inch of forward wedging surface for propelling a stream of articles that may be two inches or more in depth. In such case the tendency would be for the helix to act positively on only the lower layers of the stream. The feed would be thus much less positive and would allow much more slip than the high ribs of the prior art. Such a continuous helix can be built up from such sections and with a plurality of such helices, analogous to a 70 2-thread or 3-thread screw, the forwardly wedged-

75 ing surface area may be multiplied so as to give a practically useful rate of feed, but I have discovered that even when built from these rectangular sections only 1 inch high by 1½ inches wide, a continuous helix of conventional pitch, is likely to cause distortion of the inner shell.

80 Ultimately I discovered that it is not necessary to have the helix sections continuous; that I can provide propelling surface adapted to ensure a constant uniform flow of the material through the furnace, by widely interrupting and uniformly distributing the sections, in flight formation; and that many advantages result. The total forward wedging area may be multiplied as much as may be desired; the forward wedging angle of the flights 85 may be selected, independently of any helical relation between them; the flights being low as compared with the depth of the stream of articles, the mixing of the articles in the stream will be thorough and will be uniform throughout the length of the furnace; and the heating will be correspondingly uniform.

90 Structurally considered, the pitch of the flights may be about the same as that common for the single helix of the prior art, so that they contribute longitudinal, as well as circumferential reinforcement for the inner lining. Apparently also diagonal stresses due to contraction and expansion of the distributed diagonal flights have much less tendency to cause distortion of said inner lining, than would a single helix of the same total length. This is particularly true when the flights are secured in accordance with my present invention, by riveting and welding at selected points, 95 widely spaced apart longitudinally of the flight. 30

100 There is of course latitude for considerable variations in the forward wedging angle of the flights, the number of flights, and their distribution, but the arrangement shown herein has proved highly successful in practice as concerns uniformly feeding a relatively deep stream of the articles through the furnace; and uniformly mixing the stream so that all articles are heated uniformly. This applies as to a wide variety of products to be heated, my furnace having been successfully used 105 where the stream consists of small articles, such as nuts for quarter inch bolts, as well as large articles, such as bolts 6½ inches long by 1½ inches in diameter; the flights being an inch high and the thickest part of the stream about 2 inches 110 deep. As shown in Fig. 1a, the flights were secured by widely spaced rivets 9x, supplemented by welding the flight to the inner shell, adjacent the rivets only, as diagrammatically indicated at 9y.

115 There are, of course, many geometrical patterns 55 whereby the desired length of flight, affording the desired total forward wedging area, may be attained. On superficial consideration, Fig. 1 might seem to indicate three helical threads, each interrupted by wide spaces between the ends of successive flights. Such an arrangement would be practical, but as a matter of fact, uniform distribution of the flights, as well as flexibility as concerns designing the length and feed pitch of the flights, was actually attained by following a somewhat different geometrical theory. This is best seen by reference to the diagram Fig. 2, which shows the geometrical relation of the flights, with respect to the direction of gravity and rotation, the internal surface of the shell being unrolled 120 to a flat, vertical plane, and the flights being identified by the same numbers as used in Fig. 1.

125 This diagram covers the exit end and a characteristic adjacent length of the inner shell. This is partly for the purpose of showing the cooper- 76

ative relation of the flights at the exit end, with respect to the outlet opening 8x.

The arrangement of the flights follows a hypothetical helical thread indicated by the dotted line 5 b—c, and other lines parallel therewith. This hypothetical thread would have a feed pitch of about 9°; but instead of having continuous rib sections along this helical line, the sections have been pitched 16° rearward of the hypothetical helix 10 line b—c. Thus the actual feed pitch of each flight with respect to the gravity line a—b, is about 25°. This approaches, but is slightly less than the feed angles used for the continuous helix 15 shown in the above specified Rockwell patent.

15 Preferably, the upper end of each flight aligns horizontally with the lower end of the flight next above it, as for instance, any flight 8 with respect to the next flight 8a; 8a—8b; etc.

20 The flight length is such that there are 3½ flights, 8, 8a, 8b and half of 8c, for each 360° turn 25 of the hypothetical helix. (See also Fig. 4.) The point about this is that having an odd half flight per 360° turn, brings the middle of every flight in horizontal alignment with the ends of adjacent 30 flights in front of, and behind it.

25 In the direction of gravity, the discharge end of each flight aligns vertically with the center of the next flight below it. When the flights are on the upturning side, as shown in Fig. 2, this puts 30 successive flights in a sort of cascade relation with respect to the down tumbling nuts. Thus, a nut tumbling over the edge of the lower half of one flight, is likely to be intercepted by the forward feed surface of the next lower flight. Furthermore, 35 when the flights are on the down turning side, near the bottom (see Fig. 1), the leading ends of successive flights, cut into the stream of nuts at a point back of where they would be if each flight had been high enough to positively screw propel 40 all nuts in its path, instead of allowing those in the top layer to tumble over its top edge.

45 Considering the flights further with respect to the hypothetical helix lines b—c, along which they are arranged, it will be seen that, because of the odd half flight per turn, all relations of the flights can be shown only by considering 7 flights that make two turns of said helix; and that is why the flights are separately identified on the drawings as 8, 8a, 8b, 8c, 8d, 8e, 8f; and it is only 50 after 8f that the arrangement repeats, beginning again with another flight 9.

55 Inspection of Fig. 1 will show that in this special case, there are six of these complete series of flights beginning with a flight 8, and as each series has seven flights, there are approximately 42 flights. In this case, the flight-equipped length of the inner shell, was about 13 feet, and its inner surface was about 7 feet 2 inches in circumference; and for these dimensions, each flight 60 was made approximately 26½ inches long; so the total flight length figures out about 93 feet for this 13 feet length of inner shell.

65 If the same 25° flights were arranged as a continuous 25° helix, the total flight length would be only 45 feet, or less. Thus two such continuous helices, arranged like a two-thread screw, would afford less flight length than is afforded by the present interrupted flight relation. Obviously, any such two-thread screw arrangement, could 70 be improved by two features of my present invention. One would be arranging them so that joints between sections in one helix are in horizontal alignment with the center of adjacent sections in the other thread, thereby contributing toward 75 more uniform structural stiffness of the inner

shell!. Another would be spacing apart the ends of all sections far enough so that nuts or bolts could not lodge between them.

Even where widely separated, uniformly distributed flights are used in accordance with all 5 the basic principles of my present invention, it will be obvious that either the pitch of the hypothetical helix or the feed pitch of the flights, or both, may be varied. Preferably, increase of feed pitch of the flights would be accompanied by increase in pitch of the hypothetical helix and vice versa. Moreover, it is not necessary that either the hypothetical helix, or the feed pitch of the flights, be the same throughout the entire length of the inner shell; and though desirable, it is 15 not essential to have the length or spacings of the flights the same. Variations may be desirable for the purpose of expediting distribution and streaming out, of the articles dumped in at the supply end of the furnace, or to slow down the 20 feed through the middle zone of the furnace, or to accelerate discharge through the hot end.

25 Certain details of the individual flights have specific advantages, regardless of how they are distributed. Having it rectangular in cross-section ensures a front propelling face perpendicular to the inner surface of the shell, so that there is less tendency for the stream of articles to slip over the top surface of the flight. Having the cross-section uniform as well as rectangular 30 throughout the length of the flight, decreases tendency to unequal expansion and distortion when heated. Having it of less height than the deepest part of the stream of articles propelled thereby tends to keep the temperature lower and 35 more uniform. Having it of greater width than height gives more uniform temperature between the hot top surface of the flight and the portion of the inner lining in contact with the bottom surface thereof. Every fraction of an inch decrease in height of a flight gives more than proportional decrease in the straightening and 40 distorting effects which normally result from any given difference in temperature between a top surface of a flight and a radially remote bottom 45 surface. Having short flights, limits the amount of distortion that can be applied at any one place on the inner shell, by end to end lengthening, straightening or distortion of the flight.

50 Any and all of the above advantages may be cheaply and easily attained by forming the flights from rolled rectangular bars, cut to proper length and bent to shape suitable for riveting and welding to the inner shell at a plurality of suitably spaced points, as above described. These 55 bars may be of any sufficiently heat resisting metal, but I prefer a nickel-chrome alloy such as Misco.

I claim:

60 1. A tubular furnace, means for peripherally supporting and rotating it to advance a stream of articles or materials therethrough, and means for projecting a flame jet in the opposite direction; said furnace including an outer shell; spaced-apart, inwardly-extending annular bearings carried by said outer shell; a cylindrical, single-piece inner shell constructed of heat-resisting plate or heavy sheet metal, fitting and longitudinally splined to said bearings; and refractory heat-insulating aggregate packed in the 70 interspaces between said shells and said bearings; said inner shell extending beyond the outer shell at the exit end of the furnace and having there- 75 in an annulus of refractory heat insulating material formed with internal diverging surfaces serv-

ing as an expansion nozzle for a flame jet projected therethrough.

2. A tubular furnace, means for peripherally supporting and rotating it to advance a stream of articles or materials therethrough, and means for projecting a flame jet in the opposite direction; said furnace including an outer shell; spaced-apart, inwardly-extending annular bearings carried by said outer shell; a cylindrical, single-piece inner shell constructed of heat-resisting plate or heavy sheet metal, fitting and longitudinally splined to said bearings; and refractory heat-insulating aggregate packed in the interspaces between said shells and said bearings.

15 3. A tubular furnace, means for peripherally supporting and rotating it to advance a stream of articles or materials therethrough, and means for projecting a flame jet in the opposite direction; said furnace including an outer shell; spaced-apart, inwardly-extending annular bearings carried by said outer shell; and a cylindrical, single-piece inner shell constructed of heat-resisting plate or heavy sheet metal, fitting and longitudinally splined to said bearings.

25 4. A tubular furnace, means for peripherally supporting and rotating it to advance a stream of articles or materials therethrough, and means for projecting a flame jet in the opposite direction; said furnace including an outer shell; spaced-apart, inwardly-extending annular bearings carried by said outer shell; and a cylindrical, single-piece inner shell constructed of heat-resisting plate or heavy sheet metal, fitting and longitudinally splined to said bearings; said inner shell extending beyond the outer shell at the exit end of the furnace and having therein an annulus of refractory heat insulating material formed with internal diverging surfaces serving as an expansion nozzle for a flame jet projected therethrough.

40 5. A tubular furnace, means for peripherally supporting and rotating it to advance a stream of articles or materials therethrough, and means for projecting a flame jet in the opposite direction; said furnace including an outer shell; a single-piece inner shell longitudinally slidable in said outer shell to permit lengthening when heated, and anchored to it only in a short zone intermediate its ends, so that said inner shell is free to slide in both directions from said anchorage when longitudinally expanded or contracted by heating or cooling of the furnace.

45 6. A tubular furnace, means for peripherally supporting and rotating it to advance a stream of articles or materials therethrough, and means for projecting a flame jet in the opposite direction; said furnace including an outer tubular shell of rolled steel capable of supporting the entire load of the furnace; spaced-apart, inwardly-extending annular bearings carried by said outer shell; a single-piece inner shell of rolled plate or heavy sheet, heat-resisting steel, longitudinally slidable to permit it to lengthen when heated; and means for anchoring only a short portion of its length to said outer shell.

55 7. A tubular furnace, means for peripherally supporting and rotating it to advance a stream of articles or materials therethrough, and means for projecting a flame jet in the opposite direction; said furnace including an outer tubular shell of rolled steel capable of supporting the entire load of the furnace; a single-piece inner shell of rolled plate or heavy sheet, heat-resisting steel, longitudinally slidable to permit it to lengthen when heated; and means for anchoring a short portion

of its length to said outer shell, to limit endwise sliding except by endwise lengthening.

8. A substantially horizontal tubular furnace, means for peripherally supporting and rotating it to advance a stream of articles or materials therethrough, and means for projecting a flame jet in the opposite direction; said furnace including an outer tubular shell capable of supporting the entire load of the furnace and having inwardly extending annular bearings having keyways formed therein, and a single-piece inner shell having walls of rolled plate or heavy sheet, heat-resisting steel; with external rigidly-secured longitudinal ribs adapted to engage said keyways, and internal rigidly-secured, inwardly-projecting, diagonally-disposed, forwardly feeding ribs of heat-resisting metal.

9. A substantially horizontal tubular furnace, means for peripherally supporting and rotating it to advance a stream of articles or materials therethrough, and means for projecting a flame jet in the opposite direction; said furnace including an outer tubular shell capable of supporting the entire load of the furnace and supporting, coaxially therewith, a single-piece inner shell having walls of rolled plate or heavy sheet, heat-resisting steel, having external rigidly-secured longitudinal ribs whereby the inner shell is keyed for rotation with the outer shell, and internal rigidly-secured, inwardly-projecting, diagonally-disposed, forwardly-feeding ribs of heat-resisting metal, said latter ribs being short sections of rolled bar, bent to fit the interior surface of said shell and secured thereto by riveting and welding.

35 10. A substantially horizontal tubular furnace, means for peripherally supporting and rotating it to advance a stream of articles or materials therethrough, and means for projecting a flame jet in the opposite direction; said furnace including an outer tubular shell capable of supporting the entire load of the furnace and supporting, coaxially therewith, a single-piece inner shell having walls of rolled plate or heavy sheet, heat-resisting steel, having external rigidly secured longitudinal ribs whereby the inner shell is keyed for rotation with the outer shell, and internal rigidly-secured, inwardly-projecting, diagonally-disposed, forwardly-feeding, ribs of heat-resisting metal, said latter ribs being short sections of rolled bar, bent to fit the interior surface of said shell and secured thereto by riveting and welding relatively small-area, spaced-apart portions of each rib section.

40 11. A substantially horizontal tubular furnace, means for peripherally supporting and rotating it to advance a stream of articles or materials therethrough, and means for projecting a flame jet in the opposite direction; said furnace including an outer tubular shell capable of supporting the entire load of the furnace and supporting, coaxially therewith, a single-piece inner shell having walls of rolled plate or heavy sheet, heat-resisting steel, and having inwardly-projecting, helically-disposed, forwardly-feeding, spaced apart flights of heat-resisting metal, said flights being relatively short sections of rolled bar, bent to fit the interior surface of said shell and secured thereto by riveting and welding relatively small area spaced apart portions of each flight.

45 12. A substantially horizontal tubular furnace, means for peripherally supporting and rotating it to advance a stream of articles or materials therethrough, and means for projecting a flame jet in the opposite direction; said furnace includ-

ing an outer tubular shell capable of supporting the entire load of the furnace and supporting, coaxially therewith, a single-piece inner shell having walls of rolled plate or heavy sheet, heat-resisting steel, and having inwardly-projecting, helically disposed, forwardly-feeding flights of heat-resisting metal, riveted to the inner surface thereof.

13. A substantially horizontal tubular furnace, means for peripherally supporting and rotating it to advance a stream of articles or materials therethrough, and means for projecting a flame jet in the opposite direction; said furnace including an outer tubular shell capable of supporting the entire load of the furnace and supporting, coaxially therewith, a single-piece inner shell having walls of rolled plate or heavy sheet, heat-resisting steel, and having inwardly-projecting, helically disposed, forwardly-feeding flights of heat-resisting metal, rigidly secured to the inner surface thereof, said flights being of short length as compared with a semi-circumference of said inner surface.

14. A furnace as specified in claim 13 and in which the flights are of substantially uniform, substantially rectangular cross-section.

15. A furnace as specified in claim 13 and in which the flights are of substantially uniform rectangular cross-section and are of greater width than thickness.

16. A furnace as specified in claim 13 and in which the flights are distributed with substantial uniformity and are arranged in generally helical relation but spaced-apart endwise.

17. A substantially horizontal tubular furnace, means for peripherally supporting and rotating it to advance a stream of articles or materials therethrough, and means for projecting a flame jet in the opposite direction; said furnace including an outer tubular shell of steel capable of supporting the entire load of the furnace; an inner cylinder formed from heat-resisting metal; and means for supporting said cylinder coaxially in said outer shell; said inner cylinder having integrally united with the inner surface thereof, inwardly-projecting, helically-disposed, forwardly-feeding flights made of heat-resisting metal, said flights being of short length as compared with a semi-circumference of said inner surface, and spaced-apart endwise, distances which are great as compared with the sizes of the articles to be propelled thereby.

18. A furnace as specified in claim 17 and in which the flights are distributed substantially uniformly and in overlapping relation circumferentially, with respect to gravity.

19. A furnace as specified in claim 17 and in which the flights are distributed substantially uniformly and in overlapping relation in the direction of lengthwise feed in the furnace.

20. A furnace as specified in claim 17, and in which the flights are of small height as compared with the depth of the stream of articles or materials advanced thereby.

21. A furnace as specified in claim 17 and in which the flights are of less height than the depth of the stream of articles or materials advanced thereby, and are distributed along a helical line which is of low pitch as compared with the feed pitch of the individual flights.

22. A furnace as specified in claim 17, and in which the flights are of less height than the depth of the stream of articles or materials advanced thereby, and are uniformly distributed along a

helical line the pitch of which is less than half the feed pitch of the individual flights.

23. A tubular furnace, means for peripherally supporting and rotating it to advance a stream of articles or materials therethrough, and means for projecting a flame jet in the opposite direction; said furnace including an outer shell; spaced-apart, inwardly-extending bearings carried by said outer shell; a single-piece inner shell fitting said bearings; and refractory heat insulating aggregate packed in the interspaces between said shells and said bearings; said bearings including a cylindrical bearing fitting the exterior of the inner shell, carried by an annular closure for the space between the inner and outer shells at the exit end of the furnace; an external bearing fitting the interior of said inner shell, carried by an end closure for said interspace at the entrance end of the furnace; and intermediate spaced-apart bearings, each consisting of an annulus formed as a thin metal wall substantially perpendicular to the axis of the furnace, and transversely curved in accordion-like flatings affording substantial circumferential elasticity; and means securing the flatings to the outer shell only at spaced-apart intervals permitting circumferential elastic compression of the annulus when expanded by heat.

24. A tubular furnace, means for peripherally supporting and rotating it to advance a stream of articles or materials therethrough, and means for projecting a flame jet in the opposite direction; said furnace including an outer shell; spaced-apart, inwardly-extending bearings carried by said outer shell; and a single-piece inner shell fitting said bearings; said bearings including a cylindrical bearing fitting the exterior of the inner shell, carried by an annular closure for the space between the inner and outer shells at the exit end of the furnace; and an external bearing fitting the interior of said inner shell, carried by an end closure for said interspace at the entrance end of the furnace.

25. A tubular furnace, means for peripherally supporting and rotating it to advance a stream of articles or materials therethrough, and means for projecting a flame jet in the opposite direction; said furnace including an outer shell; spaced-apart, inwardly-extending bearings carried by said outer shell; and a single-piece inner shell fitting said bearings; said bearings including spaced-apart bearings intermediate the ends of the shells, each consisting of an annulus formed as a thin metal wall substantially perpendicular to the axis of the furnace, and transversely curved in accordion-like flatings affording substantial circumferential elasticity; and means securing the flatings to the outer shell only at spaced-apart intervals permitting circumferential elastic compression of the annulus when expanded by heat.

26. A furnace as specified in claim 25, and in which each annulus is a casting of heat-resisting metal.

27. A furnace as specified in claim 25, and in which each annulus is a casting of nickel-chrome alloy.

28. A tubular furnace, means for peripherally supporting and rotating it to advance a stream of articles or materials therethrough, and means for projecting a flame jet in the opposite direction; said furnace including an outer tubular shell of rolled steel capable of supporting the entire load of the furnace; spaced-apart, inwardly-extending annular bearings carried by said

outer shell; a single-piece inner shell of rolled plate or heavy sheet, heat-resisting steel, longitudinally slidable to permit it to lengthen when heated; said inner shell having a radial exit chute 6 rigidly secured adjacent the exit end thereof, and said outer shell having rigidly secured thereto, a

tubular member fitted to the exterior of said chute, whereby the inner shell is anchored to the outer shell near the exit end thereof, to prevent endwise sliding of said inner shell except by lengthening when heated.

GEORGE F. BLASIER.
